STORAGE RACK FOR ATTACHMENT TO WALL LOCKERS OR THE LIKE

Donald E. Smith, 1671 South 50 West, Bountiful, Utah
84010, and Amasa Merrill Linford, 1720 Michigan
Ave., Salt Lake City, Utah 84108

Filed July 9, 1970, Ser. No. 23,872

Term of patent 14 years

Int. Cl. D6—04

U.S. Cl. D33—3

FIG. 1.

FIG. 2.

FIG.
3.

FIG. 4.

FIG. 5.

FIG. 6.

FIG. 1 is a front, side and top perspective view of a storage rack for attachment to wall lockers or the like showing our new design;

FIG. 2 is a front elevation view;

FIG. 3, a side elevation view, the opposite side, not shown, being the mirror image thereof;

FIG. 4, a rear elevation view;

FIG. 5, a top plan view; and

FIG. 6, a bottom plan view.

We claim:

The ornamental design for a storage rack for attachment to wall lockers or the like, substantially as shown and described.
